UNITED STATES PATENT OFFICE.

CHARLES MARCUS, OF NEW YORK, N. Y.

DOORCHECK AND SIMILAR DEVICE.

Application filed September 7, 1923. Serial No. 661,416.

My invention relates to door operating mechanism of the general class commonly known as door checks, and will be here described as embodied in a door operating mechanism, although the invention may be available, or is capable of being adapted, for other uses.

Door checks in common use include a spring which acts as a motor element to close the door after it has been opened, and the most successful devices employ hydraulic or pneumatic means, or a combination of such means, to regulate the closing movement. No simple and satisfactory friction mechanism has been suggested or employed, to my knowledge, to regulate the closing movement.

An important object of my invention is to provide simple, cheaply constructed and durable friction mechanism to regulate the closing movement, in connection with a suitable spring.

Another object is to provide a movable friction element or "actuator" which is itself frictionally actuated by a movable part of the device to apply proper retarding friction during the closing movement.

A further object is to provide such a friction element which is to a certain extent spring-operated or spring-controlled, or which is affected by relatively fixed and movable inclined surfaces such as screw threads; and preferably to provide such a friction element which is controlled by the combined effects of a spring and such inclined surfaces.

The invention in the physical embodiment herein represented, briefly described, comprises an element designed for connection or substantially immovable attachment to a door or door casing, a relatively movable element adapted for connection to the other part of the door structure, the relatively movable parts having co-operating friction surfaces or an interposed friction element, a motor spring, an actuator or pressure member adapted to be moved by frictional co-operation with the movable element, a controlling or regulating spring acting upon the actuator or pressure member, and inclined surfaces such as screw threads co-operating with the actuator or pressure member.

The characteristics and advantages of the invention are further sufficiently explained in connection with the following detail de-

scription of the accompanying drawings, which show one exemplifying embodiment of the invention. After considering this embodiment, persons skilled in the art will understand that many modifications may be made, and I contemplate the employment of any structures which are properly within the scope of the appended claims.

Figure 1 is a section in the plane of the spindle axis.

Figure 2 is a view, partly in bottom plan, and partly in transverse section on different planes.

Figure 3 shows the device attached to a door and door frame in one suitable way.

Figure 4 is a torque diagram.

The casing 1, of generally cylindrical form, is provided with flanges 2 and suitable bolt holes for attachment to a door D, Figure 3. The upper casing end or wall 3 may be integral with the cylindrical side wall, and the casing bottom may be closed by a cover 4 detachably secured by screws 5. A shaft or spindle 6 passes centrally through the casing and is immovably secured in any suitable way; for instance, the spindle has a threaded portion 7 screwed into a threaded sleeve 8 of cover 4, and desirably, the spindle also has a shoulder 9 which is firmly seated against the interior face of the cover when the spindle is screwed in tight; and the spindle may further be locked against rotative movement by a nut 10 screwed on an outer part of the spindle and bearing against the end of sleeve 8.

A friction disc 11 is operatively connected or integral with a sleeve 12, rotatively mounted on an upper portion 13 of the spindle, the sleeve also having a bearing fit in an aperture 14 of the housing top plate 3. The sleeve 12 or an inward part of friction disc 11 rests on a shoulder 15 of the spindle and a nut 16 may be screwed on the upper end of the spindle in opposed relation to the upper end of sleeve 12, with suitable clearance to provide for wear of friction surfaces. A lever arm 17 of suitable length is provided with a hub 18 nonrotatively secured to sleeve 12 in any suitable way, for instance, by a key 19, and the hub may be further secured against endwise displacement by a nut 20 screwed on the upper end of the sleeve. At the outer end of arm 17 is a ball 21 or any other suitable device for connecting to the arm a suitable link 22, Figure 3, which is also pivotally secured to

a bracket 23 which is secured to the door casing or frame F. In some cases the check casing 1 might be secured to the frame and bracket 23 would in that case be secured 5 to the door; but the other arrangement, as shown in Figure 3 is customary and preferred in most cases.

A motor spring 25 of suitable form and strength is located in the casing. This 10 spring is usually of helical form and is most conveniently located near the cylindrical casing wall 1. One end of the spring has an outwardly turned member or toe 26 which is secured in any convenient way in fixed 15 position in the casing, for instance, by forming a notch in the outer surface of wall 1, in which the toe 26 is located and secured by cover 4. The other end of the spring has an upwardly turned member or toe 27 which 20 is located in one of a series of notches 28 formed in the periphery of friction disc 11. While in some cases externally operated means may be provided for adjusting spring 25, in the present instance the spring adjustment 25 is effected while cover 4 is removed by placing spring member or toe 27 in a suitable notch 28 to give the desired spring tension and motive effect for closing the door.

Evidently the motor spring is not necessarily included in the present apparatus, or 30 enclosed within the casing 1. The controlling mechanism will obviously act to control door movement when the motor spring or equivalent device is applied in any manner 35 to close the door after it has been opened.

A friction disc 30, which may otherwise be identified as a flange, or as a pressure member, or in combination with connected screw threads or other inclined surfaces, may be 40 designated as an actuator, is arranged in parallel relation to friction disc 11. Disc 30 is connected to or operatively integral with a sleeve 31, the inner surface of which is provided with one or more suitable screw 45 threads 32 cooperating with screw threads 33 formed on the spindle. In a broad aspect of the invention these screw threads represent any suitable inclined surfaces for moving or urging the sleeve or the actuator consisting of the sleeve and its flange 30, in the 50 direction of the spindle axis when a rotative effort is applied to the flange 30 by frictional cooperation with disc 11. The pitch of the screw threads or other inclined surfaces may 55 be varied within suitable limits as sufficiently explained hereafter. A substantial thread clearance, sufficiently represented at 34, is also preferably provided for reasons explained hereafter.

60 An inner portion of housing end 3 is provided with a friction surface 40 cooperating with or confronting the upper friction surface of disc 11, and preferably an annular disc 41 of suitable friction material is located 65 between these surfaces, and this disc may be

secured by rivets or otherwise to casing end 3 or to disc 11, or it may be free to move 70 rotatively in respect to both of said members. Similarly, disc 11 and disc 30 have engaging or confronting friction surfaces, 75 and preferably an annular disc 42 of suitable friction material, similarly secured or freely mounted, is provided to take the friction wear between these discs. In the present specific embodiment, both the discs 41 80 and 42 are secured to disc 11 by rivets 43.

The movement or action of flange 30 or the combined flange and sleeve 31 is preferably controlled by a spring and in the present specific embodiment of the invention such 85 an actuator or controlling spring is represented by helical spring 50, one end of which bears against flange or disc 30 and the other end bears against a part of the casing or the casing cover 4. To provide for convenient adjustment of spring 50, its outer end 90 desirably rests against a suitable plurality of evenly spaced pins 51 which pass through guide-holes in cover 4, and the outer ends of the pins in turn rest against an adjusting 95 flange or nut 52, which has threaded engagement with the outer surface of sleeve 8. When desired, a nut 53 may be provided to lock the adjusting flange in adjusted position.

With the device set up as shown in Figure 3, and with a right-hand screw thread on spindle 6, as shown in Figure 1, when the door is opened, arm 17 moves clockwise in relation to the casing and spindle 6. Disc 11 connected to the arm through sleeve 12 100 moves along with the arm, and disc 30 which is held in frictional engagement with disc 11 by the pressure of spring 15 rotates clockwise along with disc 11, until clearance between the screw threads 32 and 33 is taken 105 up, this take-up requiring only a small angle of door movement. Thereupon the upper surfaces of screw threads 32 encounter the lower surfaces of threads 33, and disc 30 is retracted or tends to be retracted against 110 the pressure of spring 50 to an extent depending on the spring pressure and the pitch angle of the screw threads. As soon as the disc 30 is retracted very slightly in the axial direction, it ceases to rotate and thereafter disc 11 or its friction disc 42 slips on the friction surface of disc 30 with very much reduced or in some cases substantially negligible friction resistance to the door-opening movement. During the opening 115 movement motor spring 25 is coiled up tighter by the engagement of its end 27 with the periphery of disc 11. When the door is released the motor spring immediately commences to close it. In the closing movement, arm 17 moves counter-clockwise (Figure 3) or the end of the arm moves toward the observer in Figure 1. During the first part of the closing movement (represented by a 120 small angle of door movement) disc 30 125

moves along with disc 11 and the only resistance to the closing movement is that due to friction between disc 11 or its friction member 41 and surface 40 of the housing, 5 this friction pressure being due to the end thrust of spring 50 without amplification by the screw threads. In other words, during the first small angle of closing movement there is very little or a substantially 10 negligible resistance to the motive effect of spring 25 and the closing movement of the door therefore commences promptly and the door picks up speed with desirable rapidity. When the thread clearance is taken up, the 15 lower surface of screw threads 32 encounter the upper surfaces of threads 33, and thereupon the angularity of the screw threads urges disc 30 upward with increased pressure, this depending on the thread pitch 20 angle of the screw and the pressure of spring 50. Disc 30 is now prevented from further rotation and disc 11 moves in frictional contact with disc 30 and the friction surface 40 of the casing. A suitable vigorous retarding effect is thus applied to arm 25 17 to properly retard or check the door, the maximum retardation being built up rapidly or practically immediately after the thread clearance is taken up, and continuing 30 through the closing movement. The effect upon the door movement, however, is a variable one, due to the varying angularities of arm 17 and link 22 as shown in Figure 3, and is better understood from the diagram, 35 Figure 4. In the diagram, line A shows that the motive effect or torque of motor spring 25 is practically constant, and line B shows that while the actual friction retarding effect imposed on arm 17 is practically 40 constant throughout its stroke (disregarding the slight angle of free movement provided by thread clearance), the effective torque acting to close the door varies throughout the movement, being high 45 at the beginning of the closing movement (indicated by 0° in the diagram) and decreasing rapidly toward the mid-angle of movement, and then increasing gradually until the closing torque near the end of the movement is relatively high, and sufficient to insure proper latching of the door.

As above stated, the angle of the screw threads may be varied considerably. The thread pitch will not in any case be fine 55 enough to cause positive locking between disc 30 and disc 11. The steepness of the pitch may be increased in an extreme case up to a point where the sleeve 31 is connected to the spindle by straight splines; 60 but in that case spring 50 would exert the same friction effect in both directions of door movement. The increase of the steepness of pitch of the screw threads will therefore usually, and in preferred cases, not be 65 sufficient to eliminate the effect of the screw

threads on the spring; or otherwise stated, the angle of thread pitch is preferably within such limits that in the opening movement the friction effect, due to spring pressure, will be considerably reduced, and in 70 the closing movement the pressure effect of flange 30 will be largely amplified by the action of the screw threads.

Evidently a great many changes in construction or arrangement of parts may be 75 made and I do not limit myself to details except as claimed.

I claim:

1. An appliance for controlling doors and similar purposes, comprising relatively revolvable elements, retarding means acting by friction to retard relative movement of said elements, and frictionally operated means for varying the friction effect of said retarding means in the different directions of relative movement of said elements, said last named means including inclined members tending to increase the effective pressure and friction effect in one direction and to reduce the friction effect in the other direction of 90 movement.

2. A controller for doors and similar purposes, comprising two relatively movable members adapted to be secured or connected to relatively movable elements such as a door 95 and door frame, friction means adapted to resist relative movement of said members, an actuator for said friction means, said actuator being frictionally operated, a spring cooperating with the actuator, and means 100 tending to retract the actuator in one direction of relative movement.

3. A controller for doors and similar purposes, comprising two relatively movable members adapted to be secured or connected to relatively movable elements such as a door and door frame, a motor spring acting between said members, friction means adapted to resist relative movement of said members, an actuator, a spring cooperating with the 110 actuator, and inclined surfaces tending to retract the actuator and reduce the friction effect in one direction of relative movement of said members and to advance the actuator and increase the friction effect in the other 115 direction of relative movement.

4. A controller for doors and similar purposes, comprising a spindle adapted to be secured nonrotatively to one of two relatively movable elements, such as a door and door frame, an arm rotatable in relation to the spindle and adapted to be connected to the other of said elements, friction surfaces arranged to oppose relative movement of the arm and spindle, an actuator serving to 120 control the friction pressure, a spring acting between the actuator and a relatively fixed point, and inclined surfaces tending to amplify the friction effect in one direction of 125 relative movement of the arm and spindle, 130

and to reduce the friction effect in the other direction of relative movement.

5. A controller for doors and similar purposes, comprising a spindle adapted to be secured nonrotatively to one of two relatively movable elements, such as a door and door frame, an arm rotatable in relation to the spindle and adapted to be connected to the other of said elements, a motor spring operatively intermediate the arm and spindle, friction surfaces arranged to oppose relative movement of the arm and spindle, an actuator serving to control the friction pressure, a spring acting between the actuator and a relatively fixed point, and inclined surfaces tending to amplify the friction effect in one direction of relative movement of the arm and spindle, and to reduce the friction effect in the other direction of relative movement, clearance being provided between said surfaces to afford a small amount of relatively free actuator movement.

6. A controller for doors and similar purposes, comprising a spindle adapted to be secured nonrotatively to one of two relatively movable elements, such as a door and door frame, an arm rotatable in relation to the spindle and adapted to be connected to the other of said elements, friction surfaces arranged to oppose relative movement of the arm and spindle, an actuator serving to control the friction pressure and arranged for rotative and axial movement in relation to the spindle, a spring acting upon the actuator, and inclined surfaces tending to move the actuator axially of the spindle and amplify the friction effect in one direction of relative movement of the arm and spindle, and to reduce the friction effect in the other direction of relative movement.

7. A controller for doors and similar purposes, comprising a spindle adapted to be secured nonrotatively to one of two relatively movable elements, such as a door and door frame, an arm rotatable in relation to the spindle and adapted to be connected to the other of said elements, a motor spring, friction surfaces arranged to oppose relative movement of the arm and spindle, an actuator serving to control the friction pressure and arranged for rotative and axial movement in relation to the spindle, a spring acting upon the actuator, and inclined surfaces tending to move the actuator axially of the spindle and amplify the friction effect in one direction of relative movement of the arm and spindle, and to reduce the friction effect in the other direction of relative movement, clearance being provided between said surfaces to afford a small degree of substantially free rotative actuator movement.

8. A controller for doors and similar purposes, comprising a casing adapted to be connected to one of two relatively movable ele-

ments such as a door and its frame, a spindle secured nonrotatively to the casing, an arm mounted for rotation about the spindle and adapted to be connected to the other of said elements, a frictionally operated actuator arranged to apply frictional resistance to movement of the arm and mounted for axial and rotative movement on the spindle, cooperating screw threads on the spindle and actuator, and a spring acting between the actuator and the casing.

9. A controller for doors and similar purposes, comprising a casing adapted to be connected to one of two relatively movable elements such as a door and its frame, a spindle secured nonrotatively to the casing, an arm mounted for rotation about the spindle and adapted to be connected to the other of said elements, a frictionally operated actuator arranged to apply frictional resistance to movement of the arm and mounted for axial and rotative movement on the spindle, cooperating screw threads on the spindle and actuator, a spring acting between the actuator and the casing, and means accessible exteriorly of the casing for adjusting the last named spring.

10. A controller for doors and similar purposes, comprising a casing adapted to be connected to one of two relatively movable elements such as a door and its frame, a spindle secured nonrotatively in the casing, a sleeve mounted for rotation on the spindle, an arm on the sleeve, a friction disc on the sleeve cooperating with a fixed friction surface, a frictionally operated actuator, a controlling spring acting between the casing and the actuator, and a motor spring acting between the casing and the arm.

11. A controller for doors and similar purposes, comprising a casing adapted to be connected to one of two relatively movable elements such as a door and its frame, a spindle secured nonrotatively in the casing, a sleeve mounted for rotation on the spindle, an arm on the sleeve, a friction disc on the sleeve cooperating with a fixed friction surface, an actuator, a controlling spring acting between the casing and the actuator, and a motor spring acting between the casing and the sleeve disc, and secured at one end in one of a series of notches in the periphery of said disc.

12. A controller for doors and similar purposes, comprising a casing adapted to be connected to one of two relatively movable elements such as a door and its frame, a spindle secured nonrotatively in the casing, a sleeve mounted for rotation on the spindle, an arm on the sleeve, a friction disc on the sleeve cooperating with a fixed friction surface, an actuator, a controlling spring acting between the casing and the actuator, and a motor spring acting between the casing and the sleeve disc, and means accessible exte-

riorly of the casing for adjusting said controlling spring.

13. A controller for doors and similar purposes, comprising a casing adapted to be connected to one of two relatively movable elements such as a door and its frame, a spindle secured nonrotatively to the casing, an arm mounted for rotation about the spindle and adapted to be connected to the other of said elements, a motor spring acting between the casing and the arm, an actuator arranged to apply frictional resistance to movement of the arm and mounted for axial and rotative movement on the spindle, cooperating screw threads on the spindle and actuator, a spring acting between the actuator and the casing, a plurality of pins passing through one end of the casing and engaging the outward end of said last-named spring, and an adjustment nut having threaded engagement with an exterior part of the casing and bearing against the outer ends of the pins to adjust and form an operative abutment for said spring.

25 14. A door check or the like, comprising a substantially cylindrical casing having an open end, a cover detachably secured at that end, a spindle passing through the casing and fixedly secured in the cover, a sleeve rotatively mounted on the spindle near one end thereof and provided with a flange co-operating with a friction surface in the casing, a motor spring having one of its ends secured to the casing and its other end secured to said flange, an arm secured to said sleeve exteriorly of the casing, an actuator including a sleeve having screw-thread engagement with the spindle and a friction disc operatively connected with the sleeve, said friction disc having a surface cooperating with the friction surface of said flange, and a controlling spring acting between the casing cover and the actuator.

45 15. A door check or the like, comprising a substantially cylindrical casing having an open end, a cover detachably secured at that end, a spindle passing through the casing and fixedly secured in the cover, a sleeve rotatively mounted on the spindle near one end thereof and provided with a flange co-operating with a friction surface in the casing, a motor spring having one of its ends secured to the casing and its other end secured to said flange, an arm secured to said sleeve exteriorly of the casing, an actuator including a sleeve having screw-thread engagement with the spindle and a friction disc operatively connected with the sleeve, said friction disc having a surface cooperating with the friction surface of said flange, and a helical controlling spring within the cas-

ing and exerting thrust against the actuator tending to move it axially and to produce friction contact between the actuator disc, the flange and the casing.

65 16. A door check or the like, comprising a substantially cylindrical casing having an open end, a cover detachably secured at that end, a spindle passing through the casing and fixedly secured in the cover, a sleeve rotatively mounted on the spindle near one end thereof and provided with a flange co-operating with a friction surface in the casing, a motor spring having one of its ends secured to the casing and its other end secured to said flange, an arm secured to said sleeve exteriorly of the casing, an actuator including a sleeve having screw-thread engagement with the spindle and a friction disc operatively connected with the sleeve, substantial clearance being provided between the spindle and the sleeve threads.

70 17. In apparatus of the class described, a casing, a relatively revolute lever, a spring tending to move the lever in one direction in relation to the casing, relatively fixed and movable friction members, and frictionally-operated means acting during movement of the lever in one direction to urge the friction members in frictional contact and resist such lever movement and also acting during opposite lever movement to substantially eliminate the friction pressure.

75 18. An appliance of the class described comprising a lever, a mounting on which the lever is supported for oscillation, relatively fixed and movable friction members, a spring, and an actuator frictionally operated by movement of one of the said friction members and co-operating with the spring to urge the friction members into slipping frictional contact during movement of the lever in one direction and acting to relieve the friction pressure in the other direction of lever movement.

80 105 19. An appliance of the class described comprising a lever, a mounting on which the lever is supported for oscillation, relatively fixed and movable members, a pressure spring, a frictionally operated actuator co-operating with the spring to urge the friction members into frictional contact, and a screw-threaded element co-operating with the actuator to make frictional resistance more effective during lever movement in one direction and substantially ineffective in the other direction of lever movement.

110 Signed at Hoboken in the county of Hudson and State of New Jersey this 27th day of August A. D. 1923.

CHARLES MARCUS.
